UNITED STATES PATENT OFFICE.

ALOIS SCHULTE, OF QUINCY, ILLINOIS.

BATTERY CLAMP.

Application filed November 6, 1922. Serial No. 599,371.

To all whom it may concern:

Be it known that I, ALOIS SCHULTE, a citizen of the United States, residing at Quincy, in the county of Adams and State of Illinois, have invented certain new and useful Improvements in Battery Clamps, of which the following is a description.

My invention relates to improvements in battery clamps, and more particularly to a clamp of such a character used for the purpose of connecting the terminal lead of a battery post.

One of the objects of my invention is to provide a clamp of the kind described which will firmly hold the battery post in place in a good electrical contact without the necessity of soldering the connection thereat.

Another object of my invention is to provide a battery clamp of the kind described which, while composed of several parts, may be assembled so as to be substantially unitary and without danger of the parts disengaging during use, packing, shipping, or the like.

Other objects of my invention are the production of a device of the kind described which will be simple, compact, durable, economical, convenient, efficient and satisfactory for use wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a plan view of the device as applied to a battery post and viewed from above;

Fig. 2 is a longitudinal section view therethrough;

Fig. 3 is a sectional view taken substantially on the line 3—3 of Fig. 1;

Fig. 4 is a sectional view taken substantially on the line 4—4 of Fig. 1;

Fig. 5 is a top plan view of the clamping block, and

Fig. 6 is an end view thereof.

In the drawings, wherein I have illustrated the preferred embodiment of my invention, 1 indicates the terminal lead which is to be connected to a battery post 2. The connector or clamp for securing the terminal lead to the battery post comprises a yoked member 3, having a recess or elongated slot 4 therethrough, one end of said slot being preferably curved or arcuate, as at 5, to fit the post, the center of the arc 65 being of a radius substantially equal to that of the radius of the battery post. However, in case the battery post is formed with a cross section other than cylindrical, the clamp end 5 is of course correspondingly 70 formed to conform to the shape of the post. The other end of the slot may be curved, as at 6, if so desired, although this is not essential. Offset from the yoked portion 3 and integral therewith is an arm 7, having 75 a bore 8 therein adapted to snugly receive the terminal lead 1, which may be retained therein in any suitable manner, the axis of the bore 8 preferably intersecting the center of the circle from which the arc 80 5 is drawn.

It will be noted that the yoke member 3 is reduced in thickness between the opposite ends of the slot so as to provide shoulders or abutments 9 at the battery post receiving 85 end of said yoke, and that there is a threaded boss 10 provided at the other end of the yoke through which a set-screw 11, having an outer end or head 12, may be adjustably inserted. The inner end of the set-screw is 90 formed with a reduced neck portion 13, and the tip of said screw beyond the neck portion is enlarged as at 14, for a purpose to be more clearly hereinafter described.

Slidably or adjustably positioned within 95 the slot 4 and removable therefrom is a clamping block 15, having one end arcuately recessed, as at 16, said arcuate recess or face opposing the arcuate end of the slot 4. The sides of the clamping block opposite the 100 walls of the slot 4, are preferably channel-shaped, the flanges 17 of said channel overhanging the side walls of the slot 4 and spaced apart therefrom a distance to permit considerable play between the block and the 105 yoke portion of the clamp. The wall of the block forming the inner surface or web of the channel is similarly spaced away from the cooperating surface of the yoke, as at 18, at both sides of the block, so as to permit 110

play between the block and the yoke transversely of the direction in which the screw 11 extends, and transversely to the direction in which the play between the flanges 17 is permitted. By providing the play as hereinbefore described it is possible to get a perfect fit or contact between the clamping block and battery post and so compensate for any irregularities therein. In order that 10 the block 15 may be detachably held in place, the meeting edge of one of its walls 18 and the top wall 19 is beveled or cut away, as at 20, the other edge between the top wall and the other wall 18 being also removed in 15 a manner to be hereinafter described, so that the block may be rotated in the slot to disengage the shoulders 17 therefrom and permit the block to drop out or be lifted out.

Through the top wall 19 of the block an 20 opening 21 is formed, said opening extending to one of the sides 18, and of a size to rotatably receive the reduced neck portion 13 of the screw. This opening is undercut from the side 18 below the surface 19, as at 25 22, to provide an enlarged chamber below the opening 21, and through which the enlarged portion 14 of the screw may be inserted from said side of the block. Fig. 2 illustrates the manner in which the block is 30 released from the screw 11, or is brought into operative engagement therewith, it being apparent that said engagement or release may take place simply by rotating the block in the manner shown. When the 35 block is in the position shown in full lines, it may be reciprocated either to clamp against the battery post or moved in a direction away therefrom, simply by actuating the screw 11, its reciprocatory movement being limited by the shoulders 9 and the boss 10. By forming the clamp in the manner above described, the parts may be constructed inexpensively, and be assembled for packing and will stand any amount of handling 40 without becoming disengaged from one another, and yet, although the device is substantially unitary, the block may be removed from the device for any purpose, as 45 for renewal, inspection or the like.

50 Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure 60 by Letters Patent is:

1. A battery connector comprising means for attachment to a terminal lead, a battery-post-receiving part having a slotted yoke, a clamping block removably positioned in said 65 yoke and slidably and rotatably movable

therein to engage said battery post, and means detachably engageable with said block for reciprocatorily moving it in the yoke, but normally preventing disengagement therewith. 70

2. A battery connector comprising means for connection to a terminal lead, a battery-post-receiving part having a slotted yoke, a clamping block slidable in said yoke to engage the battery post, the opposed surfaces 75 of said block and yoke spaced apart to provide play therebetween in a pair of mutually transverse directions, but not sufficient to permit the block to drop through said yoke, said block having portions thereof removed so that it may be rotated within said yoke and be removed therefrom, and means detachably engageable with said block for adjustably holding it in position. 80

3. A battery connector comprising means 85 for attachment to a terminal lead, a battery-post-receiving part having a slotted yoke, a clamping block slidable in said yoke and provided with channelled sides whose flanges 90 overhang the opposite sides of the yoke and normally prevent the block from dropping therethrough, one face of said block cut away to engageably receive said battery post and the opposite face having an opening 95 therein extending laterally to one of said channelled sides, said opening being undercut below said last-mentioned face to provide overhanging shoulders extending inwardly from said last-mentioned channelled side, said last-mentioned face being bevelled 100 at one edge, whereby the block may be rotated in the yoke and removed therefrom, and a screw adjustably secured in the yoke to extend therewith and having an enlarged end to enter laterally in the opening in the block from the channelled side thereof and to bear against the under surface of said shoulders overhanging the undercut opening. 105

4. A battery connector comprising means 110 for connection to a terminal lead, a battery-post-receiving part having a slotted yoke, a clamping block slidable in said yoke and having play therewith and engageable with the battery post, said block being rotatable within said yoke so that it may be removed 115 therefrom, and means detachably engageable with said block for holding it in adjusted position.

5. A battery connector comprising means 120 for attachment to a terminal lead, a battery-post-receiving part having a slotted yoke, a clamping block slidable in said yoke and provided with a flange overhanging the yoke, one face of said block cut away to engage 125 said battery post and the opposite face having an opening therein extending laterally to one of the sides, said opening being undercut to provide an over-hanging shoulder extending inwardly from said last-mentioned side, said last-mentioned face being 130

bevelled at one edge so that the block may be rotated in the yoke and removed therefrom, and means adjustably secured in the yoke and having an enlarged end to enter laterally in the opening in the block and to bear against the under surface of said shoulder that overhangs the undercut opening.

In testimony whereof, I have hereunto assinged my name in the presence of two sub-scribing witnesses.

ALOIS SCHULTE.
